DESIGN FOR A BLOUSE

Rose A. Weiss, New York, N. Y.

Application July 25, 1936, Serial No. 64,052

Term of patent 3½ years

To all whom it may concern:

Be it known that I, Rose A. Weiss, a citizen of the United States of America, residing in the city of New York, county of New York, and State of New York, have invented a new, original, and ornamental Design for a Blouse, of which the following is a specification, reference being had to the accompanying drawing, forming part thereof.

Fig. 1 is a front view of a blouse showing my new design.

Fig. 2 is a rear view of the blouse shown in Fig. 1.

I claim:

The ornamental design for a blouse substantially as shown.

ROSE A. WEISS.
